UNITED STATES PATENT OFFICE

DONALD F. SPROUL, OF CHICAGO, ILLINOIS, ASSIGNOR TO UNION DRAFT GEAR CO., A CORPORATION OF DELAWARE

DRAFT GEAR

Application filed February 17, 1926, Serial No. 88,809. Renewed March 26, 1928.

The invention relates to draft gears of the friction type adapted especially for use in connection with freight cars.

Its objects are to secure a high degree of efficiency, simplicity of construction, and certainty of release.

A preferred embodiment of the invention is hereinafter described, and is illustrated in the accompanying drawings, in which

10 Fig. 1 is a central longitudinal plan section of the gear as applied to a railway car, and is shown in release position;

15 Fig. 2 is a plan view of the gear under compression in buff, some of the parts being broken away and some of the parts being shown in section;

Fig. 3 is a transverse central vertical section;

20 Fig. 4 is a longitudinal vertical central section, the gear being in release position;

Fig. 5 is a similar view, the gear being shown under compression in draft;

25 Fig. 6 is a view in perspective of one-half of one of the casing elements of the gear cut on its central longitudinal vertical plane; and

Fig. 7 is a view in perspective of one of the wedge shoes forming an element of the gear.

30 For the purpose of showing the application of the gear to a railway car, there is represented a pair of center or draft sills 10, 10, each being provided with the usual draft lugs 11, 11, and buffing lugs 12, 12.

35 A coupler butt is shown at 13 and its yoke or extension at 14. These elements form no part of the invention, and may be of any desired construction.

40 A pair of follower members 15, 16, cooperate, respectively, with the draft and buffing lugs, and directly associated with each follower member is a casing 17, 18, having integral top, bottom and side walls, and being open at both its inner and outer ends. Inasmuch as these casings are always seated against the follower members they are made as separate elements only for convenience of manufacture and assembly and for permitting the use of different character of metal 45 in the casings and follower members. The

follower members and corresponding casings constitute what for convenience of description will be termed the follower means.

Each of the casings 17, 18, is provided with wedge faces, as 19, preferably formed integral therewith and associated with the outer end of each side wall. Each of these wedge faces is inclined outwardly from the rear end of the casing, that is to say, toward the middle of the gear, in order that it may 55 have a compressive action as the gear is closed.

Associated with each of these wedge surfaces, and cooperating therewith, is a shoe 20, the inner surface of which, facing the 60 longitudinal center of the gear, is flat.

Interposed between the shoes 20 at opposite sides of the gear is a group of intercalating friction plates 21, the group being composed of two sets of plates 22, 23, the one 65 cooperating with the forward and the other with the rearward follower.

A set of powerful springs, preferably four in number, as shown at 24, 25, 26, 27, react directly between the two casings, which are 70 recessed, as shown at 28, to receive these springs, the recesses extending to the outer end of the casing in order that the length of the springs may be substantially equal to the 75 normal distance between the two follower members.

A pair of springs 29, 30, react, respectively, directly between the two shoes 20 at each side of the gear, and are of less power than the set of springs cooperating with the casings.

Each of the friction plates of the group 90 21 is provided near its rearward end with a pair of forwardly facing shoulders 31, 32, for engagement with a pair of retracting bars 33, 34. These bars are engaged, upon release, by shoulders 35, 36, formed on the top and bottom walls of the casing 17. The shoes 20 are provided with rearwardly facing shoulders 37 for engaging the bars, as 33, as the gear releases. The shoulders, as 31, of the friction plates are so spaced from the rearward ends of the plates that in release position the bars, as 33, under the influence 95 of the shoulders of the casings, will not carry 100

the butts of the plates back into contact with the follower. While the retractive movement of the shoes, as 20, under the influence of the springs 29, 30, tends to move the 5 retracting bars still farther back, this movement is arrested by the frictional engagement of the shoes with the wedging surfaces of the casings before the butts of the plates reach the followers, and hence the butts of 10 the friction plates are always normally slightly removed from the followers when the gear is in release position.

As either follower is advanced the friction plates are put under pressure by the cooperative 15 action of the wedges before any movement of the plates takes place, and the shoulders, 35, 36, of the casing, and 37 of the shoes, are moved out of contact with the retracting bars at that end of the gear. As the movement 20 of the casing commences before that of the shoes, and the casing advances slightly more than the shoes, the shoulders 35, 36, are moved farther from the bars than are the shoulders 37. When the advancing follower 25 makes contact with the ends of the plates adjacent to it these plates are carried forward with the wedging elements, and because of their frictional engagement with the other set of plates immediately bring the 30 latter into contact with the follower with which their butts are associated. The movement of the latter set of plates being now arrested, the advancing plates move relatively to them, developing a high degree of friction 35 and consequently absorbing the compressing pressure which is being exerted upon the gear, this friction being augmented by the action of the wedges at the opposite end. The walls of the casings are of such 40 length that the two casings come into contact when the desired limit of compressive movement has been reached.

Upon the removal of the compressing pressure the springs 24 to 27 immediately start 45 the advanced casing backwardly, and the compressive wedging action is immediately relieved. The backward movement of the advanced shoes commences substantially simultaneously with that of the casing. The 50 shoulders of the retracting shoes make contact with the releasing bars before they are engaged by the casing shoulders, and as the plates are still under compression, especially at their farther ends, and as the bars can move backwardly only as the set of advanced plates are withdrawn, the shoes are retarded, 55 permitting the further separation of the co-operating wedging faces. When the casing 60 shoulders engage the releasing bars the plates are carried back by the full spring pressure.

The backward movement of the advanced plates carries back the other set of plates until their shoulders engage the releasing 65 bars at that end of the gear, and the corre-

sponding shoes are, by the same means, withdrawn.

The invention is of wider scope than the specific embodiment disclosed.

I claim as my invention—

1. In a draft gear, in combination, a pair of opposed casings each having flaring forwardly facing wedge surfaces, wedge shoes cooperating with the several casing wedge surfaces, a group of intercalating plates interposed between the shoes on opposite sides of the gear, springs reacting between the casings, springs reacting between the shoes on corresponding sides of the gear, retracting bars engaging each set of plates, and retracting shoulders on the casings for engaging the bars on release. 70

2. In a draft gear, in combination, a pair of opposed casings each having flaring forwardly facing wedge surfaces, wedge shoes cooperating with the several casing wedge surfaces, a group of intercalating plates interposed between the shoes on opposite sides of the gear, springs reacting between the casings, springs reacting between the shoes on corresponding sides of the gear, retracting bars engaging each set of plates, and retracting shoulders on the casings for engaging the bars on release. 80 75

3. In a draft gear, in combination, a pair of opposed casings each having wedge surfaces converging toward the outer end of the casing, wedge shoes cooperating with the several casing wedge surfaces, a group of intercalating plates interposed between the 100 shoes on opposite sides of the gear, springs reacting between the casings, springs reacting between the shoes on corresponding sides of the gear, retracting bars engaging each set of plates, retracting shoulders on the casings for engaging the bars on release, the distance from the casing shoulders to the follower at each end of the gear being greater than the distance from the outer ends of the plates to the shoulder engaging faces of the 110 bars whereby when said gear is in normal release position the outer ends of said plates will be spaced from said followers. 105

4. In a draft gear, in combination, a pair of opposed casings each having wedge surfaces converging toward the outer end of the casing, substantially rectangular in cross section wedge shoes cooperating with the several casing wedge surfaces, a group of intercalating plates interposed between the 120 shoes on opposite sides of the gear, springs reacting between the casings at the four corners thereof, and extending substantially the full length of the gear, springs reacting between the shoes on corresponding sides of the gear, retracting bars engaging each set of plates, retracting shoulders on the casings and shoes for engaging the bars on release, said casings being adapted to engage to prevent abnormal compression of the gear. 125 130

5. In a draft gear, in combination, a pair of opposed follower members, a casing extending inwardly from each of said members, wedge faces within each casing, wedge faced
5 shoes co-operating with the several first-named set of wedge faces, intercalating friction plates located between the shoes at opposite sides of the gear, resilient means for resisting compression of said gear, and for
10 returning the parts to normal position after release, means for operatively connecting the shoes and casing successively with the plates during release action.

6. In a draft gear, a pair of follower
15 means, a group of intercalated friction plates between said follower means and adapted to be operated thereby, wedge mechanism at each side of said group of plates at each end thereof, resilient means for resisting relative
20 movement of the parts of said mechanism during compression, and means including retracting bars and shoulders on said follower means and on said wedge mechanism for engaging said retracting bars for retracting
25 said plates and for restoring the parts to normal position after compression.

In testimony whereof I affix my signature.
DONALD F. SPROUL.

CERTIFICATE OF CORRECTION.

PatentNo. 1,868,295.

July 19, 1932.

DONALD F. SPROUL.

It is hereby certified that error appears in the printed specification of the above numbered patent requiring correction as follows: Page 2, line 115, claim 4, after the word "casings" insert the words and comma substantially rectangular in cross section,; and lines 117 and 118, same claim, strike out the words substantially rectangular in cross section; and that the said Letters Patent should be read with these corrections therein that the same may conform to the record of the case in the Patent Office.

Signed and sealed this 11th day of October, A. D. 1932.

**M. J. Moore,
Acting Commissioner of Patents.**
